[57] **CLAIM**

The ornamental design for a bin with cover, as shown and described.

DESCRIPTION

FIG. 1 is a perspective view of a bin with cover, showing my new design;

FIG. 2 is a perspective view of the bin with the cover removed.

FIG. 3 is a side elevational view of the bin of FIG. 1;

FIG. 4 is a plan view of the bin of FIG. 1;

FIG. 5 is a side elevation of the bin of FIG. 1; and,

FIG. 6 is a perspective view of the bin when collapsed into the base.
